BATTERY CHARGER

Clyde Shuler, Media, and Charles J. Godfrey, Philadelphia, Pa., assignors, by mesne assignments, to Sterlingworth Company, Philadelphia, Pa., a corporation of Delaware

Application July 28, 1950, Serial No. 11,446

Term of patent 14 years

(Cl. D26—5)

To all whom it may concern:

Be it known that we, Clyde Shuler and Charles J. Godfrey, citizens of the United States and residents of Media, in the county of Delaware and State of Pennsylvania, and Philadelphia, in the county of Philadelphia and State of Pennsylvania, respectively, have invented a new, original, and ornamental Design for a Battery Charger, of which the following is a specification, reference being had to the accompanying drawings, forming a part thereof.

Fig. 1 is a perspective view of a battery charger with the cover closed, showing the front and one side of our new design;

Fig. 2 is a perspective view of the same with the cover open, showing the front and the other side thereof;

Fig. 3 is a side elevation thereof showing the cover open, and

Fig. 4 is a rear elevation thereof showing the cover open.

The characteristic features of our design reside in the portions shown in full lines in the drawings.

We claim:

The ornamental design for a battery charger, substantially as shown and described.

CLYDE SHULER.
CHARLES J. GODFREY.
